UNITED STATES PATENT OFFICE.

JAMES B. JOHNSON, OF SAN FRANCISCO, CALIFORNIA.

IMPROVEMENT IN AMALGAMATING-BARRELS.

Specification forming part of Letters Patent No. 43,507, dated July 12, 1864.

To all whom it may concern :

Be it known that I, J. B. JOHNSON, of the city and county of San Francisco, and State of California, have invented a new and Improved Method of Making Amalgamating-Barrels; and I do hereby declare that the following is a full, clear, and exact description of the construction of the same, reference being had to the accompanying drawings, making a part of this specification.

Figure 1 presents an elevation of the exterior of the barrel. Fig. 2 is a section through the center, giving a view of the inner wood casing. Fig. 3 is an end view, with a portion of the end removed so as to show the ends of wood lining.

The outer casing or shell is of iron or other suitable material, and that represented in the drawings is made in four pieces, exclusive of the ends, one of which pieces is represented in Fig. 1 at A. The pieces are formed with flanges F, by means of which they are connected together, forming a perfect cylinder. C is the cover of the orifice through which the pulp and quicksilver is introduced into the barrel. B is a bar to fasten the cover down. O is an opening in the wood casing with bars across the same, as shown in Fig. 2. This opening is directly in line with the cover C.

W W are wood with the grain running toward the inside of the barrel and form a casing around the entire inside circumference of the barrel, and are kept in position by being dovetailed into the outside shell, A, as shown in Fig. 3, or in any other suitable manner.

The outside ends of the barrel are made of iron or other suitable material, and are formed with an outside rim, R, and cross arms S S, to which are attached the journals J J. These ends have also an inside lining, L, of wood. The rims R have ears E E upon them, through which pass the bolts D D, for the purpose of securing them to the barrel.

Operation: The method of operation is similar to that of any other amalgamating barrel, and I do not claim as new the lining of amalgamating-barrels with wood.

What I claim as my invention, and for which I desire Letters Patent to issue, is—

Forming the outer shell of the amalgamating barrel or cylinder in several longitudinal sections, so that they may be easily taken apart and relined, substantially as and for the purpose described.

JAS. B. JOHNSON.
